UNITED STATES PATENT OFFICE.

MYRON E. OLSON AND VICTOR C. OLSON, OF GRAND ISLAND, NEBRASKA.

HYDROCARBON BURNER.

Application filed February 12, 1925. Serial No. 8,756.

To all whom it may concern:

Be it known that we, MYRON E. OLSON and VICTOR C. OLSON, citizens of the United States, residing at Grand Island, in the 5 county of Hall and State of Nebraska, have invented certain new and useful Improvements in Hydrocarbon Burners, of which the following is a specification.

This invention relates to an improved hydrocarbon burner and seeks, among other objects, to provide a device of this character which will be possessed of superior heat generating qualities but which will consume a relatively small quantity of fuel.

10 A further object of the invention is to provide a burner which will function to effectively gasify the liquid fuel and wherein the fuel gas will be mixed with a proper quantity of air to produce a highly combustible and practically smokeless fuel mixture, the mixture only, being consumed.

Another object of the invention is to provide a burner which will be noiseless in operation, which may be readily cleaned, 25 and which will be adapted to the use of low grade fuels.

And the invention seeks, as a still further object, to provide a burner which will be characterized by structural simplicity and which may be readily produced.

Other and incidental objects will appear hereinafter.

In the accompanying drawings:

Figure 1 is a vertical sectional view taken 35 medially through our improved burner.

Figure 2 is a horizontal sectional view on the line 2-2 of Figure 1, looking in the direction indicated by the arrows.

In carrying the invention into effect, we 40 employ a circular bowl having a flat bottom wall 10 and an upstanding annular side wall 11 thicker than the bottom wall. Integral with the bottom wall is an upstanding axially disposed air tube or flue 12 terminating flush with the upper edge of the side wall 11, and formed in said side wall is an annular ledge or seat 13. Snugly but 45 removably fitting in said seat is an annular generating plate 14 which forms a closure for the bowl and cooperates therewith to define a retort chamber 15 within the bowl. The plate 14 is provided with a flat bottom face stepped adjacent the periphery of 50 said plate to rest in the seat 13, and extending through the plate and through the wall 11 of the bowl are bolts 15' removably se-

curing the plate in position. The upper face of the plate 14 is of frusto conical outline, and formed in said plate is a central opening freely accommodating the flue so that a 55 relatively narrow annular gas passage 16 is defined between the inner circumference of said plate and the flue. At its outer periphery, the plate lies flush with the upper end edge of the side wall 11 and, as will be seen, the plate is gradually tapered in thickness from its outer periphery to the central opening of the plate. Formed on said plate at its lower side are, as particularly shown in Figure 2, rows of radially spaced depending 60 heat conducting lugs 17 terminating close to the bottom wall 10 of the bowl. Communicating with the retort chamber 15 through the bottom wall 10 of the bowl is a fuel inlet 18, and engaged with the flue 12 near its upper end, is an overflow pipe 19. Any approved means may be provided for regulating the flow of fuel through the inlet 18 to the retort chamber while any approved 65 automatic cut off may be provided in conjunction with the overflow pipe 19 to control the inlet of fuel and prevent the overflow of the bowl.

Supported by the flue 12 at its upper end 70 is a circular spreader 20 overhanging said flue and of a radius slightly less than twice the major radius of the flue so that the periphery of the spreader lies substantially midway between the wall of the flue and the outer periphery of the plate 14. Rising 75 from the conical upper side of the spreader is an apertured lug 21 by which the spreader may be lifted, and depending from the lower side of the spreader axially thereof is 80 a spreader cone 22 extending into the flue 12. Radiating from said cone, as best shown in Figure 2, are a plurality of spacing ribs or flanges 23 notched at their outer ends to fit over the upper end edge of the flue. The 85 ribs 23 thus support the spreader in spaced relation to the upper end of the flue and will maintain the spreader centered with respect to the flue. As will be observed, the lower face of the spreader is flat. Consequently, the spreader gradually approaches the conical upper face of the plate 14 toward its outer periphery to define a restricted annular burner passage 24 between the periphery of the spreader and said plate. 90 The spreader is, of course, an integral structure.

In use, liquid fuel is admitted through

the inlet 18 to the chamber 15 until the fuel rises through the passage 16 and overflows the inner margin of the generating plate 14. The fuel above said plate is then 5 ignited. As the fuel is consumed and the burner becomes heated, the level of the fuel drops to a point within the chamber 15 so that the passage 16 is opened for the flow of gas from said chamber, which gas rises 10 through said passage to strike the spreader 20 and is ignited at the burner passage 24 at the periphery of the spreader. The plate 14 with its lugs 17 is thus heated to a high temperature and since said lugs are either 15 partially or wholly submerged by the liquid fuel in the chamber 15, the heat is conducted by the lugs directly to the fuel. Effective gasification of the liquid fuel is thus accomplished. Air passing up through the 20 flue 12 supplies a draft so that the air is caused to strike the spreader 20 and is fanned out thereby in a circular sheet to flow over the upper end of the flue and consequently, across the passage 16 to become 25 mixed with the fuel gas beneath the peripheral margin of the spreader. This mixing of the air and fuel gas is accentuated by the presence of the restricted burner passage 24 at the periphery of the spreader. The tendency of this restricted passage is to cause the sheet of air flowing beneath the flat face of the spreader and the sheet of gas flowing over the conical face of the plate 14 to impinge each other at or near the throat of 30 said passage, with the result that the air and gas are commingled to produce a highly combustible fuel mixture issuing through said passage. Ignition then takes place so that an annular sheet of flame is produced, which sheet of flame is impelled by 35 the draft through the flue 12 to flow over the generating plate 14 beyond the periphery of the bowl. The burner is thus peculiarly efficient and functions to produce a 40 flame of intense heat. As will be appreciated, the spreader 20 may be readily lifted 45

from the flue 12, when the generating plate 14 may be displaced. Consequently, the interior of the bowl may be easily cleaned as may also the spreader and generating 50 plate.

Having thus described the invention, what we claim is:

1. A burner of the character specified, comprising a bowl including a flat annular bottom, inner and outer circular walls rising from the inner and outer margins of the bottom to approximately the same height, an annular plate seated upon the outer wall and spaced at its inner edge from the inner 55 wall and having its lower face flat and spaced some distance from the flat annular bottom of the bowl and provided with depending projections terminating adjacent the said annular bottom, and having its upper face outwardly flared, means securing the annular plate to the outer wall and bottom of the bowl, and a spreader supported wholly upon the inner wall and overhanging it and the inner portion of the annular 60 plate.

2. A burner of the character specified, comprising a bowl including a flat annular bottom, inner and outer circular walls rising from the inner and outer margins of the 75 bottom to approximately the same height, an annular plate removably seated upon the outer wall and spaced at its inner edge from the inner wall and having its upper face outwardly flared and provided upon its 80 lower face with depending projections terminating adjacent the said bottom, and a spreader having a cone and radial ribs upon its bottom side, overlying the inner wall and annular plate and spaced and centered 85 by the said ribs engaging over and within the said inner annular wall.

In testimony whereof we affix our signatures.

MYRON E. OLSON. [L.S.]
VICTOR C. OLSON. [L.S.]
